UNITED STATES PATENT OFFICE.

FRANK E. HOOD, JANET E. HOOD, AND ALEXANDER G. MORRISON, OF SAN FRANCISCO,
CALIFORNIA.

WINDOW VALANCE.

Application filed September 24, 1924. Serial No. 739,608.

The present invention relates to improvements in window valances, and one of its objects is to provide a simple means in connection with a window valance for preventing the lower border of the same from curling under the influence of sunshine. Our invention has particular reference to valances made of oilcloth material or other material having substantially the same characteristics. Valances as generally made at the present time are not equipped with means for preventing a curling of the lower edges and are usually rendered unsightly after they have been hanging for a short period of time only because the edges tend to curl, particularly where the bottom line of the valance is shaped to present projecting configurations. It is proposed in the present invention to provide a very simple means for preventing this curling, which consists in attaching a piece of material corresponding to the material of the valance to the lower border thereof, whereby the latter is reinforced and provided with additional weight. Practical experience has shown that valances thus prepared do not yield to the action of sunshine or other influences, but remain perfectly straight.

It is further proposed to provide means in the present invention for producing a fringe effect along the lower border of the valance. Where fringes are used at the present time they soon become tangled or curl or otherwise become unsightly. In the present invention the lower border of the valance is stenciled or marked to present parallel vertical stripes or bars made in simulation of fringes and particularly adapted to serve this purpose. In view of the fact that the bottom border is prevented from curling by the reinforcing strip, the fringe effect will never be disturbed and therefore proves superior to actual fringes.

The preferred form of the invention is illustrated in the accompanying drawing, in which Figure 1 shows a valance having our lining attached thereto and showing the means for producing the fringe effect, Figure 2 a section taken along line II-II of Figure 1, and Figure 3 a cross-sectional illustration of means for securing our strip to the valance in a case where only one face of the latter is finished. While we have shown only the preferred form of the invention, it should be understood that various changes or modifications may be made within the scope of the

claims hereto attached without departing from the spirit of the invention.

In Figure 1 the valance 1 is shown as presenting a shaped bottom edge 5, with comparatively large depending configurations 7. Our strip of material 9 is cut to follow the lower contour of the valance and to terminate in a horizontal line at the top. The strip is preferably made of material corresponding to the material of the valance and it is assumed that the valance material as well as the material of the strip as shown in Figure 1 are finished on both sides, and in the latter case the strip 9 is glued to the valance as may be seen from Figure 2.

The configurations 7 are separated by the straight lines 8 running parallel to the top of the valance, and a tassel 11 may be used for opposing any curling tendency around the short straight lines 8.

In Figure 3 is shown a cross-sectional view illustrating the manner of securing our strip to the valance in a case where only one face of the latter as well as of the strip is finished while the other face is left rough. In this case we preferably secure the strip to the valance by interposing a sheet of rubber 12 between the strip and the valance and heating the assembled materials, whereby firm and lasting union is established between the same.

To produce the fringe effect previously mentioned, we mark the bottom border of the valance with straight parallel lines or bars 13, preferably equidistant from one another and substantially of the same length. Dots 14 above the lines or bars are made to simulate the points of attachment for the fringes. A slight change in the shades of the bars may be made to simulate a wave in the fringes.

The advantages of our invention will be readily understood from the foregoing description. It is apparent that the application of our strip to the lower border requires little effort and adds only a little to the cost of manufacturing the valance. It is practical and absolutely prevents curling of the bottom edge of the valance and will keep the valance in a presentable condition throughout its life, while at the same time a fringe effect is produced which is of the same lasting quality as the material itself.

We claim:

1. A suspended valance having a shaped bottom edge and having shaped sections of the said edge weighted uniformly.

2. A suspended valance having a shaped bottom edge and having shaped sections of the said edge weighted uniformly up to a straight horizontal line.
- 5 3. A suspended valance having a shaped bottom edge, and having strips of similar material glued to shaped bottom sections for uniformly weighting the same.
4. A suspended valance having a shaped bottom edge, and having strips of similar material glued to shaped bottom sections for uniformly weighting the same, the said strips terminating in a horizontal top line. 10
